E. ERICKSON.
CEMENTING MACHINE.
APPLICATION FILED JULY 25, 1907.

1,118,542.

Patented Nov. 24, 1914.

2 SHEETS—SHEET 2.

UNITED STATES PATENT OFFICE.

EDWARD ERICKSON, OF BOSTON, MASSACHUSETTS, ASSIGNOR TO THE BOYLSTON MANUFACTURING COMPANY, OF BOSTON, MASSACHUSETTS, A CORPORATION OF NEW JERSEY.

CEMENTING-MACHINE.

1,118,542.

Specification of Letters Patent. Patented Nov. 24, 1914.

Application filed July 25, 1907. Serial No. 385,453.

To all whom it may concern:

Be it known that I, EDWARD ERICKSON, of Boston, in the county of Suffolk and State of Massachusetts, have invented certain new and useful Improvements in Cementing-Machines, of which the following is a specification.

This invention has relation to machines for applying cement or like material to a 10 surface to be coated therewith. In the manufacture of shoes, for instance, it is desirable to cement the upstanding channel flap of a sole to the face thereof, and while my invention relates more particularly to machines for coating such surfaces with cement, yet it is applicable for machines to be used in other connections.

The object of the invention is to provide certain improvements in machines of the 20 general character referred to, for more perfectly controlling the feed of the cement, preventing wastage thereof, and insuring its proper application to the surfaces to be coated.

25 In addition the invention has for its object to provide for positioning the work with respect to the brush, and for feeding the work, and for generally enhancing the efficiency of such machines.

30 Referring to the drawings which illustrate one embodiment of the invention, Figure 1 represents a side elevation of a cementing machine. Fig. 2 represents an enlarged front view of the upper portion thereof. Fig. 3 represents a longitudinal vertical section therethrough. Fig. 4 shows the position of the combined gaging and feeding device. Fig. 5 illustrates the gearing which actuates said gaging and feeding device.

40 On the drawings, 10 indicates an upright stand having at its upper end a tubular clamp 11 in which the supporting column 12 for the head of the machine is mounted. The column may be conveniently provided 45 with a laterally extended upper end to form a table 13 to receive the head. The stand and the column constitute a vertically extensible and contractible support or frame for the head on which the operative parts of the 50 machine are mounted.

The head of the machine consists of a tank or supply reservoir 14, which has an opening in the top through which cement may be introduced therein, and the opening may be 55 normally covered by any suitable closure

as indicated in dotted lines. The sides of the tank converge at their lower ends as shown in Fig. 2, so as to guide all the cement toward the outlet 15 therefrom. The tank is formed with a base 16 which rests upon the table 13 and which is removably held thereon by hinged bolts or clamps 17. Below the chamber in the tank there is a cylindrical pump chamber 18 which extends from front to rear of the head and which communicates with the interior of the tank through the port 15'. The tank and the chamber constitute a cement receptacle. The rear end of the chamber 18 is closed by a cylinder head 19, the front end being shown as closed by a head or wall 20 cast integrally therewith. Arranged in the pump chamber is a screw conveyer or pump 21, of which the shaft 23 is journaled in the heads 19 20. The rear projecting end of the shaft is provided with fast and loose pulleys 121 122 or other suitable power-transmitting device. At the rear end of the screw is a peripheral flange 22 close to the head 19, to prevent the access of cement to the bearing for the shaft.

80 The screw conveyer or pump forces the cement which flows into the chamber from the tank into the device by which it is applied to the work. Attached to the end or head 20 of the chamber 18 is a bracket or casting 25 having forwardly extending arms 26 27 in which is journaled an upright hollow shaft or sleeve 28. The arm 27 serves as a support as well as a bearing for the sleeve 28, which, as will be explained, is the brush holder and actuator. Upon this sleeve is secured a small bevel gear 29 which intermeshes with and is driven by a bevel gear 30 secured to the forward reduced end of the shaft 23 which extends through the bracket 25 as shown in Fig. 3. The lower end of the sleeve is formed with an internally threaded socket 31 and with a peripheral flange or upper face by which it is held against the face on the frame 27 by a collar 32 which is screwed upon an annulus on the said frame. Immediately above the arm 27 is a packing ring 33 with suitable packing. The arm 27 is formed with a small chamber or cement-receiving reservoir 34 which communicates by a duct 35 with the chamber 18. This duct extends through the arm 27 and through the head 20. The lower end of the sleeve 28 is illustrated as somewhat enlarged, and it is formed with apertures 36 which 105

afford a communication between the interior of the hollow shaft or sleeve and the chamber 34. Secured into the socket in the end of the hollow shaft or sleeve, is the shank 37 of a brush. The said shank is formed with an externally threaded boss on which is secured a tapered shell or casing 38 for forming a cement receiving chamber or cavity 39, into which the cement 5 may pass through a duct 40. The shell or casing 38 has a transverse partition 41 in the center of which is secured a tube 42. Within the shell and around the tube 42 are secured a plurality of bristles, as at 43, the bristles 10 extending some little distance beyond the lower end of the tube 42. As thus described, the brush is formed with a reservoir for the cement with bristles for the application of the cement, and with means, as a tube, for 15 conducting the cement to the middle of the mass of bristles. A valve is utilized to control the flow of cement into the brush. This valve is illustrated at 44, and its conical end is adapted to be seated in the upper end of 20 the shank of the brush. The valve fits within the hollow shaft and in the position shown in Fig. 3, it prevents the passage of cement from the small chamber 34 into the hollow shaft, and from the hollow shaft into 25 the duct 40. The valve stem 45 passes upwardly through the hollow shaft and is provided with a spherical knob or head 46 which is socketed in the cup-like end 47 of a lever 48 fulcrumed between its ends upon a 30 stud 49 passed into the wall of the tank. A spring 50 has one end attached to the free end of the lever and its other end attached to a hook 51 on the exterior of the tank, and it tends to swing the lever about its fulcrum 35 so as to hold the valve against its seat to cut off the supply of cement to the brush. The free end of the lever is connected by a chain or other suitable form of connection 52 to a foot treadle 53 fulcrumed at 54 at the base 40 of the frame 10, so that the operator may open the valve to the desired extent.

In proximity to the brush, I provide a work gage 55 which is adapted to rotate. As shown, it is in the form of a frusto-cone and 55 it is mounted upon a shaft 56. This shaft is journaled near its ends in bearings 57 58, formed upon the ends of an elongated yoke or support 59. The said support is located between ears 60 which project forwardly from the arm 27 of the bracket 25, and it is provided with a curved slot 61 to receive a pin 62 passed through said ears 60. The upper end of the support is provided with laterally extending pins 63 which are seated in 60 hooks 64 projecting forwardly from the arm 26 of the bracket 25. The shaft 56 is arranged substantially in parallelism with the hollow shaft 28 and it is held yieldingly downward by a spring 65 so that the gage is 65 normally in a plane below the plane of the

end of the brush, as shown in Fig. 1. When so located, the work may be brought against the gage with the edge of the gage under or against the upturned channel flap α , and the work engaged and bodily lifted to bring the 70 work into position to receive the cement from the brush as illustrated in Fig. 4. The gage may be well utilized for the purpose of feeding the work and to this end I secure to the upper end of the shaft 56, a gear wheel 75 75 66. An elongated gear 67 is secured to the upper end of the hollow shaft 28. When the gage is in the position shown in Fig. 1, the gears are out of mesh, but when the gage is lifted into the position shown in Fig. 4, the gear 66 is caused to intermesh with the gear 67 to effect the rotation of the shaft 56, and therefore of the gage 55. To assist the intermeshing of the gears the ends of either teeth 80 are beveled or pointed as shown in Fig. 5. 85

In order that the cement may escape from the conveyer-chamber, when the valve 44 is seated, I provide a port or by-pass 75 leading from said chamber to the tank near the front end of the chamber, this port being 90 relatively small as compared with the port 15 so as not to interfere with the feeding of the cement when the valve is open.

The yoke 59 has the elongated slot 61, as hereinbefore described, so that the gage and 95 work feeding device has a limited movement transversely of the brush, for shoes having channels of different widths.

Having thus explained the nature of my 100 said invention and described a way of constructing and using the same, although without attempting to set forth all of the forms in which it may be made or all of the modes of its use, what I claim is:—

1. In a cementing apparatus, a brush, a 105 rotatable brush holder having an external cement-receiving reservoir adjacent thereto, a valve controlling the passage of cement from said cement-receiving reservoir to said brush, a cement-receiving chamber between 110 said brush and said reservoir and connecting with each, a cement supply reservoir, and mechanism between said supply reservoir and said receiving reservoir for supplying the latter and the brush with cement. 115

2. In a cementing apparatus, a brush depending from the lower end of a rotary shaft, a cement-receiving chamber adjacent thereto and exterior to said rotary shaft and connecting with said brush, a cement supply reservoir, and mechanism for forcing cement from said supply reservoir to said cement-receiving reservoir and said brush. 120

3. In a cementing apparatus, a rotary shaft, a brush depending from the lower end 125 of said shaft, a cement-receiving receptacle exterior to said shaft, a conduit leading from said receptacle to said brush, a valve controlling the passage of cement to said brush, a cement supply reservoir, a chamber 130

between said cement supply reservoir and said cement-receiving reservoir, a conduit connecting said chamber with said reservoir, and mechanism for forcing cement from said chamber to said cement-receiving reservoir.

4. In a cementing apparatus, a rotary shaft, a brush depending from the lower end of said rotary shaft, a cement-receiving reservoir exterior to said shaft and connecting with said brush, a valve for controlling the passage of cement from said reservoir to said brush, a cement supply reservoir, and a screw conveyer located between said supply reservoir and said receiving reservoir for conducting cement to said receiving reservoir and the brush, said conveyer being geared to said rotary shaft.

5. In a cementing apparatus, a rotary hollow shaft, having openings in its sides, a brush depending from the lower end of said shaft, a cement-receiving reservoir exterior to said shaft and communicating with said openings, a passageway between said receiving reservoir and said brush, a valve controlling said passageway, a cement supply reservoir, a chamber located beneath said supply reservoir and between it and said cement-receiving reservoir, a conduit connecting said chamber and said reservoir, and mechanism for forcing cement to said receiving reservoir and said brush.

6. In a cementing machine, a rotatable brush having bristles longitudinal of its axis and adapted to apply cement to the flat marginal surface of a sole with which a marginal flap is joined, and a rotary gage disposed to engage the flat surface of the sole within the flap, said brush and gage being rotatable about approximately parallel axes and being separated by a clear space through which the flap may be fed without obstruction.

7. In a cementing machine, a rotary bristle brush having its bristles projecting lengthwise of its axis of rotation, and a rotary gage, said brush and gage being arranged to present their ends to the same side of a sole, and separated from each other by a clear space through which an upturned flap of the sole may be fed without obstruction.

8. A cementing apparatus comprising a rotary brush, means for supplying cement to said brush, a rotary work gage, mechanism for operating said work gage, and means for connecting said gage at will with said mechanism, said gage being adapted to engage and feed the work.

9. A cementing apparatus comprising a rotary brush, means for supplying cement to said brush, mechanism for rotating said brush, a vertical rotary shaft connected with and driven by said brush mechanism, a gage driven by said shaft, and spring-tension

means for moving said gage vertically, said gage being adapted to be moved to and from said brush.

10. In a cementing machine, a rotary brush having bristles extending lengthwise of its axis, and a rotary gage, said brush and gage being arranged to present their ends to the same side of a sole, and separated from each other by a clear space through which an upturned flap of the sole may be fed without obstruction, one of said elements being freely axially movable with relation to the other.

11. In a cementing machine, a rotary brush and a rotary gage both arranged to present their ends to the same side of a sole, and separated from each other by a clear space through which an upturned flap of the sole may be fed without obstruction, one of said elements being axially movable with relation to the other, and means for connecting them whereby rotation of one is transmitted to the other.

12. A cementing apparatus comprising a device for applying cement, and a rotatable shaft having a work gage thereon, said shaft being axially movable substantially for the purpose set forth.

13. A cementing apparatus comprising a rotary brush, a shaft for rotating said brush, a work gage, a shaft therefor, and gears on said shafts whereby one imparts rotation to the other.

14. In a cementing apparatus, a rotary hollow sleeve having one or more lateral apertures, a stationary device inclosing a portion of said sleeve and having a chamber communicating with said apertures, a brush carried by said sleeve, means for supplying cement to said chamber, a valve in said sleeve for controlling the passage of cement to said brush, and a treadle for sliding said valve.

15. In a cementing apparatus, a hollow rotary brush-holder having a valve seat, a brush below said seat having a duct leading from the valve seat through said brush, a slideable valve in said brush-holder, and means for sliding said valve to and from its seat while said brush is in rotation, comprising a lever connected to said valve and movable about its fulcrum to slide said valve.

16. In a cementing apparatus, a hollow rotary brush-holder, a brush having substantially parallel bristles in the end thereof adapted to receive cement therefrom, a stationary cement reservoir communicating with the interior of said brush-holder, a valve controlling the passage of cement from the holder to the brush, a lever connected to said valve, a spring which tends to close said valve, and manually operable means for rocking said lever to open said valve.

17. In a cementing apparatus, a rotary brush, a work gage movable relatively to the brush, and means rendered active on a movement of said gage for rotating said gage.
18. In a cementing machine, a rotary brush having its bristles arranged lengthwise of its axis for applying cement to the flat marginal surface of a sole with which a channel flap is joined, and a gage disposed to engage the flat of the sole within such flap and leave the flap free for feeding movement, said gage being freely movable bodily in a line substantially parallel to the axis of said brush.
19. In a cementing apparatus, a rotary brush-holder, a substantially cylindrical brush having substantially parallel bristles carried by said brush, a frusto-conical gage whose axis is substantially parallel to the axis of said brush-holder, and mechanism for rotating said brush and said gage.
20. In a cementing machine, a rotary cement-applying brush and a rotary gage whose axes of rotation are substantially parallel but offset laterally from each other, the peripheries of the brush and gage being in confronting relation but separated from each other to receive a channel flap between them and supporting shafts for said brush and gage respectively, projecting in the same direction substantially in parallelism.
21. In a cementing machine, a rotary actuator, a cement-applying brush thereon, and a rotary gage arranged at the side of the brush, said gage being freely movable longitudinally of its axis of rotation by the pressure of the work thereagainst.
22. In a cementing machine, a rotary actuator, a cement-applying brush thereon, a rotary gage arranged at the side of the brush, and means for movably mounting said gage whereby it is adapted freely to move along its axis of rotation toward and from said brush.
23. In a cementing machine, a rotary actuator, a cement-applying brush thereon, a rotary gage arranged at the side of the brush, and a spring exerting its tension to move said gage along its axis of rotation.
24. In a cementing machine, a brush adapted to engage the work on one side of the channel flap, and a rotatable gage, freely movable longitudinally of its axis by pressure of the work thereagainst and on the other side of said channel flap.
25. In a cementing machine, a brush, a gage and means for rotating said brush and said gage in opposite directions about their respective axes.
26. In a cementing machine, a rotary brush, means for supplying cement thereto, a support and actuator for the brush, a valve supported by said actuator and having a spherical head projecting beyond the actuator, and a lever having a seat for said head.
27. In a cementing machine, a brush, a rotary brush holder having a cement-receiving chamber in open communication with the brush, and a pump arranged exteriorly of said brush holder and communicating with said cement-receiving chamber.
28. In a cementing machine, a brush, a rotary brush shaft having a cement-receiving chamber in open communication with the brush, a pump arranged exteriorly of said brush shaft and communicating with said cement-receiving chamber, and gearing connecting said pump and said shaft whereby one is driven by the other.
29. In a cementing apparatus, a brush, a rotary hollow shaft therefor having one or more lateral apertures, stationary means formed with a chamber inclosing a portion of said actuator and communicating with said apertures, a valve controlling the supply of cement to said brush, and a stem extending from the valve in a direction away from the brush, said valve stem having a non-threaded sliding engagement with said actuator, whereby said valve may be opened and closed when the brush is in rotation.

In testimony whereof I have affixed my signature, in presence of two witnesses.

EDWARD ERICKSON.
